UNITED STATES PATENT OFFICE.

ISAAC STEVENS, OF ROCHESTER, NEW YORK, ASSIGNOR TO YAWMAN AND ERBE MFG. CO., OF ROCHESTER, NEW YORK, A CORPORATION OF NEW YORK.

FURNITURE-MODEL.

1,374,247.

Specification of Letters Patent. Patented Apr. 12, 1921.

Application filed October 9, 1919. Serial No. 329,511.

To all whom it may concern:

Be it known that I, ISAAC STEVENS, of Rochester, in the county of Monroe and State of New York, have invented certain new and useful Improvements in Furniture-Models; and I do hereby declare the following to be a full, clear, and exact description of the same, reference being had to the accompanying drawings, forming a part of this specification, and to the reference numerals marked thereon.

My present invention relates to the construction of small models illustrative of large articles of merchandise and made of paper or similar material to be used in selling such merchandise so that the purchaser may visualize the articles offered him, and it has for its object to provide a simple, cheap and easily constructed device of this nature that will illustrate different desired combinations of sectional or elastic furniture, the materials used in the sample being in themselves elastic or interchangeable in the same manner as the goods it represents. To these and other ends the invention resides in certain improvements and combinations of parts all as will be hereinafter more fully described, the novel features being pointed out in the claims at the end of the specification.

In the drawings:

Figure 1 is a perspective view of a number of samples constructed in accordance with and illustrating one embodiment of my invention and arranged in the relative positions intended for the originals;

Fig. 2 is a plan view of one of the end portions of a sample;

Fig. 3 is a plan view of the other end portion and the top and front of the same sample;

Fig. 4 is an end elevation of the sample;

Fig. 5 is a front elevation thereof;

Fig. 6 is a transverse section through the same on the line 6—6 of Fig. 5;

Fig. 7 is a perspective view of the interior of the sample with the latter inverted, and

Fig. 8 is an enlarged detail section on the line 8—8 of Fig. 7.

Similar reference numerals throughout the several views indicate the same parts.

My invention is particularly useful in giving illustrations of the appearance of filing devices and similar sectional furniture used in offices. In Fig. 1, 1 indicates

a cardboard base made to scale to represent the floor space of an office and 2, 3 and 4 indicate the paper models of articles of furniture made to the same scale and arranged on the base in the same manner that it is proposed to arrange the furniture in the office so that the purchaser can get an idea of how his equipment will look and the space that it will occupy or leave free.

Taking, for instance, the article indicated at 3, this comprises five sections A, B, C, D and E the first consisting of a column of shallow drawers; the middle three sections separate columns of wide vertical filing drawers and the last a section of narrow filing drawers. Each of these in the real article is a separate section secured to the other to build up the complete unit. In the practice of my invention I build up the paper model in the same way. The model 3 comprises the blank shown in Fig. 3 consisting of a front portion 5, a top portion 6 and one end portion 7 all made in one integral sheet including leg extensions 8 having flaps 9 that are finally bent as shown in Fig. 7, to give them supporting capability. The top portion 6 and end portion 7 are attached to adjoining edges of the front portion 5 on scored lines 10 and 11. This blank is preferably made of blank paper, that is, unprinted, and of a length as to the portions 5 and 6 sufficient to equal the maximum number of section widths that it will be desired to represent. The end opposite to that carrying the end portion 7 (the left end in Fig. 3) is then cut off at the proper point and printed strips carrying pictures of drawer fronts as shown at 12 in Fig. 5, are pasted on the front portion 5 in abutting positions in the same manner as the sections of the real article are juxtaposed. End pictures 13 giving the appearance of the end panels that are secured to the outside sections of the real article are applied to the end portion 7 of the blank and to a separate end portion 14 shown in Fig. 2 and having attaching flaps 15 and also the leg extensions 8—9. The blank is then bent up to the block-like form of the original, as shown in Fig. 7 and Fig. 1, the end piece 14 being applied to the open end of the blank by pasting its flaps 15 to the front and top portions 5 and 6, as clearly shown in Fig. 7. A similar flap 16 on the end portion 7 is pasted to the other end edge of the top portion 6. 110

Pictures 17 representative of the material of the corresponding portion of the original and in similar sectional pieces are also pasted to the top portion 6 and these may either 5 be separate or may be extensions of the front pictures 12.

As the panel pictures 13 are usually the same for all sizes and combinations, they may, if desired, be printed directly upon 10 the end portions 7 and 14 and the legs 8 may also be permanently printed on the blank, leaving only the front portion 5 to receive its different combinations of separate section pictures.

15 With the aid of my invention all the combinations available with the actual furniture sections can be accurately reproduced to give a very pleasing and graphic representation of the appearance of the original 20 equipments to be furnished a customer as well as the relative space they will occupy.

I claim as my invention:

1. An illustrative furniture model com-

prising a front, a top and two end portions 25 of sheet material and a plurality of separate picture strips each representative of a section of elastic furniture pasted to the face of the front portion, the latter and the top being cut to a length that equals the sum of the widths of the picture strips. 30

2. An illustrative furniture model comprising a front, a top and an end portion, the two latter portions being joined to adjoining edges of the first in combination with another separate end portion having 35 flaps adapting it to be attached to the aligned edges of the other ends of the front and top after the latter have been cut to the desired length and a plurality of separate picture strips each representative of a section of 40 elastic furniture pasted to the face of the front portion, the latter and the top being cut to a length that equals the sum of the widths of the picture strips.

ISAAC STEVENS.
